UNITED STATES PATENT OFFICE

GEORGE E. KRIDER, OF DUNCANVILLE, PENNSYLVANIA, ASSIGNOR TO McLANAHAN-STONE MACHINE COMPANY, OF HOLLIDAYSBURG, PENNSYLVANIA, A CORPORATION OF PENNSYLVANIA

SCREEN

Application filed February 16, 1929. Serial No. 340,444.

The present invention relates to a screen for shifting material and has for its prime object to provide a screen of this nature which is mounted and has a motion imparted thereto for throwing the material back and forth across the screen.

A still further very important object of the invention resides in the provision of a screen of this nature in combination with means for mounting the same and imparting simultaneously thereto a transverse and a longitudinal rocking or oscillatory movement.

A still further very important object of the invention resides in the provision of an apparatus of this nature which is exceedingly simple in its construction, strong and durable, inexpensive to manufacture, thoroughly efficient and reliable in use and operation and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is a side elevation of the apparatus embodying the features of my invention,

Figure 2 is a front elevation thereof.

Figure 3 is a longitudinal vertical section therethrough,

Figure 4 is a detail view of the shaft,

Figure 5 is an end view thereof,

Figure 6 is a diagrammatic edge view of the screen showing the longitudinal oscillatory movement,

Figure 7 is a diagrammatic plan view of the screen showing the transverse oscillatory movement.

Referring to the drawing in detail it will be seen that the letter A denotes generally a supporting frame which in the present instance comprises a rectangular bottom frame 5 with a pair of legs 6 rising from the front corners thereof and a pair of legs 7 rising from the rear corners thereof and being longer than the leg 6. The numeral 8 denotes

an upper frame rectangular in formation having the legs 6 fixed at their upper ends in the front corners thereof while intermediate portions of the legs 7 are fixed in the rear corners thereof.

A cross bar 8 is mounted between the upper ends of the legs 7. The letter B denotes generally the screen member which comprises a rectangular frame 9 with a screen or sheet of foraminous material 10 mounted therein. Bearings 11 rise from the center of the intermediate portions of the frame 10 that is the side rails thereof and a shaft 12 is journaled therein.

The portions of the shaft journaled in the bearings 11 are provided with oppositely disposed eccentrics 14. This shaft 12 is journaled in bearings 15 mounted on the fore part of the side rails of the frame A. Any suitable means may be used for rotating the shaft 12.

The screen is disposed so as to incline downwardly and forwardly and is held in this position by means of a plurality of springs. A spring 16 is attached to the front of the frame A and to the front of the frame 9.

A similar spring 17 is attached to the front of the frame 5. A similar spring 18 is attached to the cross member 8 and to the rear of the frame 9. A similar spring 19 is attached to the rear of the frame 9 and to the rear of the frame 8. These springs, therefore, hold the frame in said downwardly and forwardly inclined position.

Now when rotary motion is imparted to the shaft 12 the frame 9 rocks transversely and longitudinally at the same time so as to cause the material to be thrown to and fro across the screen or foraminous sheet 10 and greatly increasing the efficiency of the sifting operation.

It is thought that the construction, operation, utility and advantages of this invention will now be quite apparent to those skilled in this art without a more detailed description thereof.

The present embodiment of the invention has been disclosed in considerable detail merely for the purposes of exemplification since in actual practice it attains the features of advantage enumerated as desirable in the

statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

In an apparatus of the class described, including a supporting frame having pairs of front and rear legs, the rear pair of legs extending above the front pair of legs and having upper and lower transverse brace bars connected to the opposite faces thereof, an inclined sifter frame including front and rear upper and lower transverse brace members, a sheet of foraminous material in the sifter frame, bearings on the sifter frame, a shaft journaled in the supporting frame and having vertically disposed eccentrics extending in opposite directions journalled in bearings to impart transverse and longitudinal rocking movement to the sifter frame, coil springs connected to the upper and lower rear brace bars of the sifter frame and anchored respectively to the upper and lower brace bars of the supporting frame, upper and lower coil springs connected to the front upper and lower brace bars of the sifter frame, and to the supporting frame adjacent to the upper and lower ends thereof.

In testimony whereof I affix my signature.

GEORGE E. KRIDER.
